UNITED STATES PATENT OFFICE.

SARAH E. L. WILSON, OF BALTIMORE, MARYLAND.

ANTICHAFING DEVICE.

SPECIFICATION forming part of Letters Patent No. 686,498, dated November 12, 1901.

Application filed September 16, 1901. Serial No. 75,575. (No model.)

To all whom it may concern:

Be it known that I, SARAH E. L. WILSON, a citizen of the United States, residing at Baltimore, State of Maryland, have invented certain new and useful Improvements in Antichafing Devices, of which the following is a specification.

This invention is an improved antichafing device intended to be worn about the thigh of a person's leg to prevent the chafing incident to the rubbing together of the thighs while walking.

The invention consists in certain constructions and arrangements of the parts of the antichafing device hereinafter fully described and claimed, reference being had to the accompanying drawings, in which—

Figure 1 is a side view of the improved antichafing device as seen when worn upon a person's thigh, a portion of the person's body and thigh being indicated in dotted lines. Fig. 2 is a front view thereof. Fig. 3 is an enlarged top plan view of the device.

As illustrated in the accompanying drawings, the improved antichafing device comprises a bandage consisting of a strip of soft and smooth elastic sheet-rubber *a* and two strips of substantially inelastic fabric *b*, which each have one edge permanently secured by stitching or the like to the ends of the rubber strip *a*, and the free edges of said inelastic fabric strips are provided with an adjustable connection. In the present instance this adjustment consists of rows of eyelets *c*, through which is threaded a lacing *d* to adjustably fasten the two ends of the bandage together. The elastic material *a* should be non-porous, as thereby it will resist the moisture of the body, and thus keep soft.

To the upper edge of one of the rearmost inelastic fabric strips *b* is permanently secured both ends of a preferably inelastic strap *e*, which forms a suspender-loop, on which a ring *f* is loosely mounted, and to said ring is secured the lower end of a preferably elastic supporting-strap *g*, the other end of which is provided with a safety-pin *h* or other detachable fastening means, whereby said strap may be secured to a waistband *i* or to any garment that may be suitable for the purpose.

In practice the bandage is placed around the upper portion of one of a person's thighs—

in this instance it is shown on the left thigh—with the smooth elastic sheet-rubber strip *a* on the inside—that is, adjacent the other leg. 55 The lacing *d* is adjusted and tied, so as to fit the bandage comfortably tight around the thigh, and the elastic supporting-strap *g* is secured to the waistband *i* or the like. With this arrangement, it is to be observed, the 60 thigh that is without the bandage will in the operation of walking or similar movements rub against the smooth and soft sheet-rubber *a*, thereby avoiding chafing of the thighs. The sheet-rubber *a* being elastic 65 will not uncomfortably bind the leg around which it is fitted, while the inelastic strips *b*, *b'* on the outer side operate to prevent the bandage from slipping around. The arrangement of elastic supporting-strap *g*, ring *f*, and 70 strap *e*, while it securely supports the bandage without the necessity of tightening the latter to too great an extent around the leg, has a draw or pull from the rearward slightly to the front, but at the same time allows perfect freedom of movement of the body with 75 respect to the bandaged leg. If desired, two antichafing devices may be used—one on each leg—instead of but one, as herein illustrated; but I have found that one alone will give 80 very good results.

I am aware that it is not broadly new to provide a device to prevent the thighs of persons from chafing, one of such devices being provided with two inelastic shields of hard 85 rubber hinged together and which inclose the scrotum and are interposed between the latter and the thighs and another of such devices being provided with shields, also inelastic, and interposed between the thighs and not 90 directly connected to the same. I therefore do not claim such constructions; but

What I do claim as new, and desire to secure by Letters Patent, is—

1. An antichafing device adapted to be worn 95 about a person's thigh, comprising a bandage consisting of a strip of soft non-porous elastic material; two substantially inelastic fabric strips each of which has one edge secured to an end of said elastic strip; an adjustable 100 connection between the free edges of said inelastic fabric strips; and supporting-straps for said bandage.

2. An antichafing device, comprising a

bandage formed of a strip of sheet-rubber, two fabric strips each of which has one edge permanently secured to an end of said rubber strip and provided in its other edge with eyelets, and a lacing threaded through said eyelets, the said bandage being adapted to be fastened around the upper portion of a person's thigh with the rubber strip adjacent the other thigh; a strap, *e*, having both ends secured to the upper edge of one of said fabric strips; a ring loose on said strap, *e*; and a support-

ing-strap having one end secured to said *e*, and provided at its other end with a detachable fastening device, as and for the purpose set forth.

In testimony whereof I affix my signature in the presence of two witnesses.

SARAH E. L. WILSON.
